UNITED STATES PATENT OFFICE.

WILBUR W. MARSH AND CHARLES H. HACKETT, OF WATERLOO, IOWA, ASSIGNEES TO SAID MARSH.

LINER FOR CENTRIFUGAL LIQUID-SEPARATORS.

No. 860,928:

Specification of Letters Patent.

Patented July 23, 1907.

Application filed February 26, 1904. Serial No. 195,388.

To all whom it may concern:

Be it known that we, WILBUR W. MARSH and CHARLES H. HACKETT, citizens of the United States of America, and residents of Waterloo, Blackhawk county, Iowa, have invented certain new and useful Improvements in Liners for Centrifugal Liquid-Separators, of which the following is a specification.

Our invention relates to improvements in liners for centrifugal liquid separators, and the object of our improvement is to provide appropriate means whereby a portion of the liquid may be conveyed directly between each adjacent set of separating disks of the liner, thereby equalizing the distribution, and utilizing the whole separating surfaces of the disks. This object we 15 have attained by the means which are hereinafter described and claimed, and which are illustrated in the drawings hereto annexed, in which—

Figure 1 is a vertical section of a liner showing our one piece corrugated distributing device therein, the 20 section being made on the line $y-y$ of Fig. 2; Fig. 2 is a plan view of said liner, a portion being sectioned off on the line $z-z$ of Fig. 1; Fig. 3 is a vertical section of a liner, on the line $w-w$ of Fig. 4, showing our separated distributing troughs inserted therein; Fig. 4 is a plan 25 view of the same liner, a portion being sectioned off on the line $z-z$ of Fig. 3, and Fig. 5 is a vertical section of a liner, on the line $w-w$ of Fig. 4, the separated distributing troughs being shown as arranged spirally within.

Similar letters refer to similar parts throughout the 30 several views.

The tendency in liners which are formed of a series of superimposed conical separating devices is for part of these devices or disks to receive a larger portion of inflowing liquid than the others, thereby causing the 35 liquid to be unequally distributed, resulting in a loss of efficiency. We have adopted a distributing device which obviates this defect in liners by conveying an approximately equal portion of the inflowing liquid to the interspace between each pair of adjacent separating 40 disks. Each separating disk is thus called upon to perform its full share of the separation, and the liner enabled to act at its full efficiency.

It is our object particularly to convey certain definite portions of the entering liquid to certain specified disks. 45 By doing this, each disk is compelled to perform its own definite share of the separation. If the entering liquid is not thus definitely deflected to certain disks, the first disks encountered by the liquid are caused to do the major part of the separating, leaving the greater 50 number of the disks ineffective. When a small part of the disks are thus over taxed, the casein in the milk soon clogs up their surfaces. Then the other disks become effective, but as a whole the bowl loses pro-

gressively most of its power to separate the constituents of the liquid.

55

When we conduct definite portions of the liquid positively to certain disks, the full extent of the bowl perpendicularly as well as radially is used, no clogging by casein results, and the maximum separation occurs.

Our improvement thus consists in the limiting of the 60 outwardly sprayed streams, by varying the lengths of the conduits so as to definitely locate the issue of the liquid to predetermined disks.

With this end in view, in a liner composed of separating disks a supported on uprights b attached to an 65 upper plate g and a lower plate h , we have introduced a depending corrugated plate c attached to an upper plate f , plate c being formed with helically arranged apertures. The plate f is detachable from the plate g , and also bears an exit tube e for the egress of the lighter 70 constituent of the liquid. Said plate c has its corrugations arranged in a series of parallel troughs with a single perforation d at the outer angle of the lower end of each trough. Each one of the perforations d is placed opposite to and communicating with one only of the 75 spaces between adjacent pairs of the separating disks b . The liquid is conveyed from without to the distributing troughs and perforations d through the holes k in the upper plate f .

Other similar modes of distributing the entering milk 80 or other liquid between the separating disks may be used but their principle is within the scope of this invention.

In Figs. 3 and 5 we have shown variations in the form 85 of the distributing device, the principle of distribution being the same.

In Fig. 3 the distributing device is shown in the shape of a number of separated single troughs c each trough being supplied with a plurality of perforations d .

The perforations d may be made of one diameter, but 90 we have shown them of diameters increasing in size from above downward. This progressive increase in the size of the perforations d is thought to be necessary because of the fact that if they were all of the same size the uppermost perforations would receive a larger 95 portion of the inflowing liquid than the lowermost ones. Enlarging the perforations therefore tends to approximately equalize the amount of liquid discharged into the spaces between the disks.

In Fig. 5 we have shown the distributing troughs c 100 as arranged spirally within the interior of the liner. It is thought that this arrangement tends to aid the flow of liquid and lessen friction.

It will of course be obvious that instead of using a series of distributing troughs each furnished with one 105 or more perforations, that one distributing trough

might be used provided with a number of perforations equal to the number of interspaces between the separating disks of the liner.

Having described our invention, what we claim as new, and desire to secure by Letters Patent, is—

5. In a liner for centrifugal liquid separators, separate means for distributing an approximately equal portion of the inflowing liquid to each of the interspaces between separate adjacent separating disks, substantially as shown and described.
10. In a liner for centrifugal liquid separators, independent means for conducting and equally apportioning the inflowing liquid to the interspaces between adjacent separating disks situated at different elevations, substantially as shown and described.
15. In a liner for centrifugal liquid separators, a series of independent means for conducting and equally apportioning the inflowing liquid to the interspaces between adjacent separating disks, substantially as described.
20. In a liner for centrifugal liquid separators, separate means having communications at different points therein with the interspaces between adjacent separating disks whereby the inflowing liquid may be equally apportioned to the interspaces, substantially as described.
25. In a liner for centrifugal liquid separators, a series of parallel conducting means adapted to equally apportion the inflowing liquid to the interspaces between the adjacent separating disks situated at different elevations, substantially as described.
30. In a liner for centrifugal liquid separators, means for equally apportioning the inflowing liquid to the interspaces between adjacent separating disks comprising a series of

troughs having openings in the angles thereof to communicate with the interspaces, and means for distributing the liquid to each of said troughs, substantially as described.

7. In a liner for centrifugal liquid separators, a series of distributing troughs for equally apportioning the inflowing liquid to the interspaces between the separating disks, substantially as described.

8. In a liner for centrifugal liquid separators, means for equally apportioning the inflowing liquid to the interspaces between separating disks comprising an upper member provided with a series of perforations therein and a series of troughs each in communication with the interspaces between the separating disks and the openings in said member, substantially as described.

9. In a liner for centrifugal liquid separators, independent means for equally apportioning the liquid to the interspaces between separating disks and means for positively distributing the liquid to said first named means, substantially as described.

10. In a liner for centrifugal liquid separators, a series of separating conduits for distributing an approximately equal portion of the inflowing liquid to each of the interspaces between adjacent separating disks, the latter situated at different elevations, substantially as described.

Signed at Waterloo, Iowa, this 13th day of February, 1904.

WILBUR W. MARSH.

CHARLES H. HACKETT.
